UNITED STATES PATENT OFFICE.

JOHN CULVER BEEKMAN, OF NEW YORK, N. Y.

DESIGN FOR A WATER-CLOSET BOWL.

SPECIFICATION forming part of Design No. 20,869, dated June 30, 1891.

Application filed June 3, 1891. Serial No. 394,963. Term of patent 14 years.

To all whom it may concern:

Be it known that I, JOHN CULVER BEEKMAN, of the city and county of New York, in the State of New York, have invented and 5 produced a new and original Design for Water-Closet Bowls, of which the following is a specification.

The leading features of my design are the representation of a series of fleur-de-lis 10 around the base of the bowl and a pair of bands or fillets spaced apart and surrounding the upper portion of the bowl, with a wreath interposed between them.

Figure 1 represents an end view of the 15 bowl, and Fig. 2 a side view.

The body of the bowl (denoted by A) is of

oval shape, its sides presenting an ogee curve. The pedestal B is of polygonal contour and is surrounded by a beaded band A' at the base of the bowl, from which the series of 20 fleur-de-lis a extend upwardly around the exterior of the bowl. The fillets or bands around the upper portion are denoted by D and the interposed wreath by d.

What I claim, and desire to secure by Letters Patent, is—

The design for water-closet bowls herein shown and described.

JOHN CULVER BEEKMAN.
